ELECTROLYTIC MANUFACTURE OF POTASSIUM PERSULPHATE

Modesto Salleras, Paris, France, assignor to Buffalo Electro-Chemical Company, Inc., a corporation of New York

Application March 31, 1938, Serial No. 199,294
In France March 31, 1937

6 Claims. (Cl. 204—82)

The direct manufacture of potassium persulphate by electrolysis of an electrolyte containing only potassium salts has not been practised heretofore on account of the low efficiency of the process. This low efficiency is due in part to the low ionic concentration of the electrolyte used, in part to deposition of persulphate on the anode and in part to reduction which occurs at the anode.

This invention relates to a process and to an electrolytic cell without a diaphragm by means of which potassium persulphate may be obtained directly from potassium salts with an energy efficiency greater than that of the known processes.

The essential feature of the process is the use of an electrolyte in which the potassium persulphate formed by the electrolysis is nearly insoluble (2.3 grams per litre of electrolyte at 15° C.). This low solubility diminishes the reduction at the cathode of the potassium persulphate formed electrolytically and avoids the necessity of using a diaphragm.

This improved electrolyte has a strong concentration of KSO_4 ion and HSO_4 ion and a correspondingly good conductivity. The energy consumption may be only 1.3 kilowatt-hours per kilo of potassium persulphate, the anodic current density being 0.5 amp. per square cm. The use of this electrolyte results therefore in a very good current and energy efficiency.

Examples of the electrolyte of the present invention in which the potassium persulphate is substantially insoluble are 3 moles of potassium bisulphate (KHSO_4) and one mole of sulphuric acid (H_2SO_4) with sufficient water to give the following composition:

98	grams H_2SO_4 per litre
430	KHSO_4
770	water

or 3 moles of potassium sulphate (K_2SO_4) and 5 moles of sulphuric acid (H_2SO_4), with sufficient water to give the following composition:

252	grams H_2SO_4 per litre
275	K_2SO_4
770	water

The electrolyte may also be prepared from other combinations of salts of the potassium and sulphate radicals, for example, by preparing a saturated aqueous solution of potassium tetralsulphate $\text{K}_2\text{S}_4\text{O}_13 \cdot 3\text{H}_2\text{O}$ and potassium bisulphate KHSO_4 in the proportion of one mole of the former and two moles of the latter.

The above examples relate to a temperature of 15° C. but the composition of the electrolyte is varied slightly with variation of temperature, but so that the potassium persulphate is substantially insoluble in the electrolyte.

The electrolytic cell comprises a substantially horizontal cathode of graphite in the form of a rectangular frame made up of two long side plates and two short end plates or distance pieces. 5 The anode is formed by a row of vertical wires generally of platinum or iridium-platinum, placed in the middle longitudinal line of the cathode frame. The wires are soldered or welded to an iron frame covered by ebonite and fixed to the cathode to form a block which is supported as a whole in the cell which may be of sandstone.

This arrangement allows of a very short inter-electrode space, a good current distribution and a very low electrical resistance. With the afore-15 said electrolyte and anodic current density the potential drop at the terminals is only about 3.8 volts.

To avoid deposition of potassium persulphate at the anode (which might diminish the current and energy efficiency), compressed air is admitted 20 into the electrolyte below the electrodes and this together with the speed of upward flow of the electrolyte has the desired effect. Besides, the expansion of the compressed air will bring about a substantial cooling of the electrolyte.

According to the invention, a constant supply of electrolyte is maintained at the lower part of the cell and a constant discharge is provided at its upper part. The speed of upward flow of the electrolyte and the compressed air forced into the electrolyte avoid the deposition of potassium persulphate at the bottom of the cell.

The accompanying drawing illustrates the invention, and the preferred form of the cell:

Fig. 1 is a diagram of the cyclic process;

Fig. 2 is a vertical cross section through the cell;

Fig. 3 is a horizontal longitudinal section on line III—III of Fig. 2.

40 Referring to Fig. 1, from a tank 10, the electrolyte flows by pipe 11 to the lower part of the electrolysis cell 12, from the upper part of which it passes through pipe 13 to a refrigerator 14 and thence through pipe 15 to a filter 16. The liquid leaving the filter 16 passes through pipe 17 into the saturator 18 where it receives any necessary additions of potassium and sulphate radicals. Pump 20 draws the regenerated electrolyte through pipe 19 and delivers it through pipe 21 to the tank 10.

45 The potassium persulphate leaves cell 12 in suspension in the electrolyte and the quantity in suspension is increased during the flow through the refrigerator and the whole is retained by the filter 16 from which it is periodically removed. The electrolyte is then forwarded back at the beginning of the cyclic process where it recovers its primary composition.

50 Referring to Figs. 2 and 3, the cell 12 is preferably constructed of stoneware and is shaped

internally to form a support 22 for the cathode composed of four thick plates 23, 24, 25, 26 fastened together to form a rectangle commensurate in length and width with the internal length and width of the cell. The means of assembling the plates (for instance screws) should be incapable of attack by the electrolyte. The current is conducted to the cathode by a graphite rod 27.

The anode consists of wires 28, preferably of iridium-platinum, held vertically in a metal frame composed of longitudinal members 29 and 30 and vertical members 31, 32 encased in ebonite or other suitable insulation. The lead for the current supply to the anode is shown at 34.

The pipe 11 shown in Fig. 1 is extended as pipe 35 through the length of the lower part of the cell and is closed at its free end, the exit for the liquor being through perforations 36 along the topmost part of the pipe; thus the electrolyte is fed uniformly throughout the length of the cell.

A outflow pipe 13 is at about the level of the upper member 29 of the anodic frame.

Compressed air is forced into the electrolyte through perforations 38 in pipe 37 placed below the cathode and extending along the cell.

The electrolyte steams through the space between the cathode and the anode and the persulphate produced is carried forward as soon as formed, an effect assisted by the streams of air from pipe 37.

It will of course be understood that the invention is not limited to the exact embodiment shown.

I claim:

1. The continuous method of producing potassium persulphate electrolytically without the use of a porous diaphragm which comprises electrolyzing a substantially saturated aqueous solution of potassium bisulphate and sulphuric acid in substantially the mole relation of three moles of potassium bisulphate to one mole of sulphuric acid while maintaining such a temperature and continuing the electrolysis that a precipitate of potassium persulphate is produced, the solution subjected to electrolysis being continuously moved between the electrolyzing electrodes and continuously removed from the cell at such a rate as to carry out the precipitated potassium persulphate and prevent deposition of the same in the cell or on the anode.

2. The continuous method of producing potassium persulphate electrolytically without the use of a porous diaphragm which comprises electrolyzing a substantially saturated aqueous solution of potassium bisulphate and sulphuric acid in substantially the mole relation of three moles of potassium bisulphate to one mole of sulphuric acid while maintaining such a temperature and continuing the electrolysis that a precipitate of potassium persulphate is produced, the solution subjected to electrolysis being continuously moved upwardly between the electrolyzing electrodes and continuously removed from the cell at such a rate as to carry out the precipitated potassium persulphate and prevent deposition of the same in the cell or on the anode.

3. The continuous method of producing potassium persulphate electrolytically without the use of a porous diaphragm which comprises electrolyzing a substantially saturated aqueous solution of potassium bisulphate and sulphuric acid in

substantially the mole relation of three moles of potassium bisulphate to one mole of sulphuric acid while maintaining such a temperature and continuing the electrolysis that a precipitate of potassium persulphate is produced, the solution subjected to electrolysis being continuously moved upwardly between the electrolyzing electrodes and continuously removed from the cell at such a rate as to carry out the precipitated potassium persulphate and prevent deposition of the same in the cell or on the anode, compressed air being discharged into the solution passing between the electrodes to aid additionally in preventing deposition of solid potassium persulphate on the anode.

4. The continuous method of producing potassium persulphate electrolytically without the use of a porous diaphragm which comprises electrolyzing a substantially saturated aqueous solution of potassium acid sulphate acidified with sulphuric acid while maintaining such a temperature and continuing the electrolysis that a precipitate of potassium persulphate is produced, the solution subjected to electrolysis being continuously moved upwardly between the electrolyzing electrodes and continuously removed from the cell at such a rate as to carry out the precipitated potassium persulphate and prevent deposition of the same in the cell or on the anode, compressed air being discharged into the solution passing between the electrodes to aid additionally in preventing deposition of solid potassium persulphate on the anode.

5. The continuous method of producing potassium persulphate electrolytically without the use of a porous diaphragm which comprises electrolyzing a substantially saturated aqueous solution of three moles of potassium bisulphate and five moles of sulphuric acid while maintaining such a temperature and continuing the electrolysis that a precipitate of potassium persulphate is produced, the solution subjected to electrolysis being continuously moved upwardly between the electrolyzing electrodes and continuously removed from the cell at such a rate as to carry out the precipitated potassium persulphate and prevent deposition of the same in the cell or on the anode, compressed air being discharged into the solution passing between the electrodes to aid additionally in preventing deposition of solid potassium persulphate on the anode.

6. The continuous method of producing potassium persulphate electrolytically without the use of a porous diaphragm which comprises electrolyzing a substantially saturated aqueous solution of two moles of potassium bisulphate and one mole of potassium tetrasulphate while maintaining such a temperature and continuing the electrolysis that a precipitate of potassium persulphate is produced, the solution subjected to electrolysis being continuously moved upwardly between the electrolyzing electrodes and continuously removed from the cell at such a rate as to carry out the precipitated potassium persulphate and prevent deposition of the same in the cell or on the anode, compressed air being discharged into the solution passing between the electrodes to aid additionally in preventing deposition of solid potassium persulphate on the anode.

MODESTO SALLERAS.
